BALLAST EXCAVATING AND CLEANING APPARATUS

Harry W. Protzeller, Fairmont, Minn., assignor to Fairmont Railway Motors, Inc., Fairmont, Minn., a corporation of Minnesota

Application October 5, 1933, Serial No. 692,249

19 Claims. (Cl. 262—2)

This invention relates to improvements in ballast excavating and cleaning apparatus and it consists of the matters herein described and more particularly pointed out in the appended 5 claims.

One of the objects of the present invention is to provide an economical and flexible apparatus for excavating and cleaning the ballast of a railway road bed as a continuous operation 10 and for relaying the cleaned ballast so as to provide a road bed having the desired drainage.

Another object of the invention is to provide an apparatus of this kind, which is efficient in operation, regardless of the type or kind of ballast found in the road bed, the variation in track 15 centers or the traffic conditions on the rail way.

Still a further object of the invention is to provide an apparatus of this kind which can readily operate on shoulders and intertrack space 20 or either thereof, and along straight track or curves, and which shall be easy to control when excavating and cleaning ballast and in being manipulated to permit passage of traffic on adjacent tracks.

Still another object of the invention is to provide an apparatus of this kind which includes a ballast excavating and cleaner box or casing along one or both sides of a car, which box or casing may be readily moved from one position 25 to another as track conditions require, and which casing may be easily adjusted as to depth, as to angularity, longitudinally, transversely and otherwise, at which it is desired to operate and this whether on shoulder or intertrack space work.

The above mentioned objects of the invention, as well as others, together with the many advantages thereof, will more fully appear as I proceed with my specification.

In the drawings:

Fig. 1 is a view in side elevation of an apparatus of the kind described embodying the preferred form of the invention and shows the ballast excavating and cleaning mechanism in its working position.

Fig. 2 is a top plan view of the same and shows the ballast excavating and cleaning mechanisms in full lines when in their working positions and in dotted lines when in their non-working positions.

Fig. 3 is a transverse vertical sectional view through a part of the apparatus on an enlarged scale as taken on the line 3—3 of Fig. 1.

Fig. 4 is a detail view in top plan elevation 55 of certain parts shown in Fig. 3.

Fig. 5 is a longitudinal sectional view through one of a plurality of hydraulic engines or cylinders embodied in the improved apparatus.

Fig. 6 is a detail horizontal sectional view through a part of the apparatus as taken on the line 6—6 of Fig. 1 and illustrates more particularly the flexible draw bar connection between one of the excavating and cleaning mechanisms and its associated hydraulic engine or cylinder.

Fig. 7 is a longitudinal detail sectional view 10 through a part of the apparatus as taken on the line 7—7 of Fig. 3.

Fig. 8 is a diagrammatic plan view illustrating more particularly the operative connection between the lateral pushing or bracing cylinders 15 and their associated ballast cleaning and excavating mechanism.

Fig. 9 is a diagrammatic view illustrating the piping for and control devices of the various hydraulic engines or cylinders embodied in the 20 apparatus.

Fig. 10 is a sectional view illustrating one of the typical four-way valves employed in the control mechanism of the apparatus and shows the same in operative relation with associated manifolds and pipes.

In general, my improved ballast cleaning apparatus includes a car adapted for travel upon a railroad track. Preferably at each side of the car is mounted a casing which includes mechanism for excavating or removing foul ballast from both the shoulder and intertrack space and for operating upon the same so that each piece of rock or stone in the removed ballast is caused to roll or rub against its neighbor, whereby the 35 dirt is quickly shaken clear and is separated from the cleaned ballast. This casing which will hereinafter be referred to for brevity as the "cleaner box", is so supported by associated mechanism that it may be projected laterally 40 from its non-working position on the car outwardly and downwardly into its working position, spaced laterally from the car. This mechanism is of a peculiar arrangement in that it can be manipulated to tilt the box in every direction to meet various working requirements.

Referring now in detail to that embodiment of the invention, illustrated in the accompanying drawings:

1 indicates as a whole a railroad car with 50 suitable framing including a center sill 2. Operatively connected to the framing are the front and rear wheeled trucks 3 and 4 respectively, for travel upon the usual rails 5. These rails are secured in the manner well known upon the ties 55.

6 which rest upon the ballast of a railroad road bed, such ballast usually being a crushed rock or stone ballast.

At the front and rear ends of the framing 5 is provided suitable platforms 7 and 8 respectively thus exposing the framing and center sill therebetween as best shown in Fig. 2. On the front end of the car is a cab 10 for the operator and in said cab are located the various controls 10 shown diagrammatically in Fig. 9 whereby the operating mechanisms of the apparatus are manipulated.

Rising from the framing at each side of the car, are pairs of front and rear upright structural posts 11 and 12 respectively, the posts 11 and 12 on the same side of the car being connected together by a fabricated beam 13. Near the posts of each pair of upright posts 11 and 12 and secured at their ends in the fabricated 20 beams 13, are pairs of longitudinally spaced, transversely extending channels 14 and 15 respectively. Disposed between each pair of channels 14 and 15 are transversely extending, projectable and retractable, cleaner box supporting members 16 and 17 respectively, each in the form of an I beam. On the channels 14 and 15 are journaled rollers 14a-15a, upon the top side of which the top flanges of the I beams constituting the members 16 and 17 engage, so as 25 to provide an antifriction mounting for the easy projection and retraction of said supporting members. This arrangement is best shown in Fig. 7. The members 16 are adapted for projection outwardly from and retraction inwardly toward 30 one side of the car and the members 17 are adapted for a similar projection and retraction with respect to the other side of the car.

Each member 16 and 17 is provided at its outer end on the top side thereof with a socket 18, 40 to receive the ball head on one end of a piston rod 19 whereby a universal joint connection is had between said socket and rod end. Each rod 19 extends through one end and into an associated hydraulic cylinder 20 and the other end of each cylinder has a ball and socket joint 45 connection with a bracket 21 suitably mounted on the associated channels 14 and 15. The rods and cylinders mentioned for the members 16 and 17 face in opposite direction. When a hydraulic motive fluid is admitted to one end of the cylinders 20, the beam members 16 and 17 are projected outwardly and when such fluid is admitted to the other end of said cylinders, said members are retracted inwardly.

Associated with the members 16-16, and 17-17 respectively, of each pair thereof, is a ballast excavating and cleaning mechanism indicated as a whole as at 22 and before referred to as the "cleaner box". The function of said mechanism is to strike off or scrape into the ballast to the desired depth to not only excavate and remove such ballast but also to clean the foul matter or dirt therefrom and then relay the cleaned ballast. Said mechanism constitutes an open box-like casing of a length approximating the distance between the pairs of members 16 and 17 and includes a pair of inner and outer upright side walls 23-23 secured together in any suitable manner. At the 60 front bottom end of each side plate is an upright gathering wing 24. Between said plates is provided a suitably driven, endless chain 25 which is trained about sprockets mounted on transverse shafts journaled in the side plates. 70 This chain has teeth thereon, which in the for-

ward movement of the car not only dig into the ballast to excavate the same but also cause the excavated ballast to travel upwardly and rearwardly over a cleaning screen 25a. In this movement of the ballast up over the screen, the various rocks or stones receive a rolling action and are caused to rub against each other and this loosens the dirt and other foul matter therefrom which falls through the screen to be discharged onto a transverse belt or conveyor, (not shown) for subsequent disposal. The cleaned ballast is discharged from the rear end of the cleaning box back upon the subgrade produced by the scraping action of the box in excavating or removing the ballast. The specific mechanism within the cleaner box forms no part of the present invention and therefore, is only referred to generally.

Each cleaner box is operatively connected at its four corners to its associated pair of supporting members 16 and 17 as follows: Each side plate of the cleaner box is provided near each end with an outwardly extending spherical socket 26. Operatively engaged in each socket is the spherical head on the bottom end of a 25 piston rod 27. The other end of each rod extends through the bottom end of and into an associated hydraulic engine or cylinder 28. Each cylinder 28 is provided at its top end with a spherical head 30 which is operatively engaged in an associated socket depending from the bottom of the associated supporting member 16-17. The cylinders 28 have operatively connected to their top and bottom ends, suitable conduits leading to and from a source of 30 hydraulic fluid under pressure. Thus such fluid may be fed into and out of said ends of the cylinders, to project and retract the various piston rods out of and into their respective cylinders. In this projection and retraction of 40 the piston rods, it is apparent that the cleaner boxes may be lowered and raised with respect to their supporting members. By raising and lowering the piston rods associated with one or the other ends of the box, its angular position may be changed as desired.

In Fig. 5, I have shown in detail on an enlarged scale, one of the hydraulic cylinders 28 and as these cylinders are substantially like other cylinders employed in the apparatus, a 50 detailed description of one cylinder 28 will suffice for all of such cylinders.

The cylinder 28 is provided at its bottom end with a stuffing box plate 31 through which the piston rod 27 slides and in said plate is provided a boss 32 by which a pipe leading to and from suitable headers or manifolds is connected to the cylinder. The socket 26 in this instance is made of a bolted together pair of 55 socket members which coact to embrace a 60 spherical head 27 on the piston rod.

The top end of the cylinder is closed by a plate 34 with which the head 30 before mentioned, is made integral. This head engages in an associated socket 35 previously mentioned depending from the under side of an associated member 16 or 17. Said socket is similar in structure to the socket 26. Also provided in the top head is a boss 36 by which a pipe leading 65 to and from suitable headers or manifolds is connected to the cylinder. On the top end of the piston rod within the cylinder is secured a piston 27a. When hydraulic fluid under pressure is admitted to one end of the cylinder, it 70

is apparent that the rod will be projected therefrom. When such fluid is admitted to the other end of the cylinder the rod is retracted into the cylinder.

5 When the apparatus is in transport from one place of use to another, the cleaner boxes rest in their non-working position upon pairs of shelves 37 extending laterally from each side of the center sill 2 between the platforms 7 and 8. Such shelves are best shown in Fig. 2.

10 When it is desired to move either one or both of the cleaner boxes into working position with respect to the ballast to be operated upon, hydraulic fluid under pressure is admitted to the inner end of the associated cylinder or cylinders 20. This will cause the associated pistons 19 to be projected outwardly with a corresponding projection of the cleaner box supporting member 16 or 17 so that the cleaner box or boxes 15 are moved outwardly off the supporting shelves 37 into a position spaced laterally from the side of the car. This position is one located above the ballast worked upon, whether the same be a part of the shoulder of the road bed or a 20 part of the intertrack space of the road bed.

25 Hydraulic fluid is now admitted to the top end of the cylinders 28 so that the associated rods 27 are projected downwardly to lower the box into substantially working position with respect to the ballast. By proper manipulation of the controls from said cylinders and which will later be described, the front or inlet end of the box may be forced to such a position as to work or dig into the ballast as the car moves 30 along the track. When the proper operating depth has been attained, the box may be held in said position by the cylinders against being forced upwardly out of the ballast by the forces offered by the ballast.

35 Between each box and the car is a flexible draw bar in the form of a linked chain 38 (see Fig. 6) and by which the box is drawn through the ballast as the apparatus as a whole moves upon the track. This chain is operatively connected at one end to the front end of the inner upright plate 23 of the box by means of brackets 39 and shear pin 40. This chain passes 40 through a guide tube 41 secured to adjacent framing and is secured at its other end to the piston rod 42 of a hydraulic cylinder 43 carried by the car at a point under the rear end of 45 deck portion 8. A ball and socket arrangement 43a, provides a universal joint connection between said cylinder and car. Should the box 50 meet an insurmountable obstruction embedded in the ballast, the pin 40 will shear or break so as to prevent undue damage to the cleaner box.

55 The cylinder 43 is provided at both ends with suitable conduits whereby hydraulic fluid under 60 pressure may be admitted to either end of the cylinder. Thus the desired fore and aft position of the box, with respect to the transverse planes of the supporting members 16 and 17 may be obtained with the assurance that said box may be rigidly held in the said desired position. When the box is moving into such a fore or aft position, the pistons 27 and cylinders 28 will assume a position slightly inclined from the perpendicular.

65 70 It is apparent that enormous forces are encountered by the cleaner box in its operation upon the ballast and such pressure may manifest itself in several ways. One of these ways is to move the box laterally inward or outward 75 and therefore some means must be provided to

counteract such forces in this respect so as to hold the box in the desired working position.

In the present instance, I provide a pair of lateral thrust opposing, extensible braces for each box which hold the boxes in working position so as to take the desired path through the ballast. Such braces each comprises a pair of hydraulic engines 44, each having a universal joint connection 45 at one end with an associated bracket 46 secured to and extending laterally 10 from the center sill 2. Slidable through the other end of the cylinder is a piston rod 47 the outer end of which has a universal joint connection 48 with the inner upright side plate 23 of the box. Each cylinder is provided with connections at both ends whereby hydraulic fluid under pressure may be admitted to either end of the cylinder. By the proper application of such fluid, the piston may be projected out of or retracted into the associated cylinder to provide that length of brace which will hold the box in the desired position. These braces normally extend downwardly and forwardly from their points of connection with the center sill when the same are in their working position. However, when said cleaner boxes are in their non-working position wherein they rest upon the shelves 37, they extend longitudinally of the car 15 as best shown in Fig. 8.

20 It is known that the inner rail of a track, 30 where the same takes a curve, is disposed at an elevation lower than that of the outside rail, due to banking, so that a car taking the curve will tilt toward the lower side of the track. With the present invention, it is apparent that 35 with the car of the apparatus taking a curve during its operation, the bottom of the cleaner box would assume an angular position disposed at a right angle to the plane of the tilt. Under such conditions, the inner side of the box operating on the high side of the track, would operate at an elevation lower than the outer side so that the subgrade made by the box in operation would cause drainage toward the track. To 40 avoid this objection, the braces and supports 45 as constituted by cylinders 44 and 28 and rods 47 and 27 respectively may be further projected or retracted as might be necessary, so that the box is caused to swing inwardly or outwardly at the bottom about its connections with the supporting members 27-28 so as to insure that the bottom will be disposed in a horizontal plane. Thus the subgrade, which really determines 50 the direction of drainage, will be even.

In Fig. 9, I have shown diagrammatically, the 55 control system for the various hydraulic cylinders. All of the controls for the system are located in the cab 10. In said Fig. 9, 49 indicates a pump driven in any suitable manner by a motor 50. 51 indicates a line leading to the 60 inlet side of the pump from an oil tank 52 and in said line is an oil screen 53. A shut-off valve 54 is provided in said line between the tank and screen and a check valve 55 is also disposed in said line near the pump.

65 70 75 56 indicates the high pressure discharge line leading from the outlet of the pump and in said line near the pump is a check valve 57, and spaced from said check valve said line is provided with a shut-off valve 58. A line 59 is connected to the line 56 at a point between the valves 57-58 and in said line 59 is a pressure relief valve 60. The line 59 is connected to the top end part of an oil reservoir 61 and the tank 52 is connected by a line 62 with the reser-

voir 61 at a point between its ends. A vent line 63 is connected to the top end of the reservoir and a line 64 connects the top of the tank 52 with the vent line 63 whereby the oil tank is 5 vented.

65—66 and 67—68 indicate respectively, pairs of sets of manifolds or headers, with one manifold of each set connected to a corresponding manifold of the adjacent set by connectors 10 69—70 and 71—72 respectively. The manifolds of the same set are connected together by connectors lines 73, 74—75—76—77, 78—79—80—81, and 82, respectively, and in each connector line just above mentioned, is a four-way valve 15 73a—74a—75a—76a—77a—78a—79a—80a—81a and 82a, respectively, the purposes of which will later appear.

The connectors 70—72 just above mentioned are connected to the line 56 by branches 83 and 20 84 respectively. The connector lines 69—71 before mentioned are connected to a line 85 by branches 85a—85a and the pipe 85 in turn communicates with the pipe 59 near the oil reservoir 61.

25 86—87 indicate the manifolds or headers of another set or pair of manifolds, the manifolds of each set being connected together by sets of connectors 88—89—90—91 and 92—93—94—95, in which are located fourway valves 88a—89a—90a—91a—92a—93a—94a—95a, respectively. The bottom manifolds of both pairs are connected by lines 96—97 with the line 85 while the top manifolds of both pairs are connected by a branch 98—99 with the lines 83—84 in turn connected to the line 56.

30 The four-way valves 89a—94a each has pair of lines 100—101 connected thereto and each line is connected to both ends of the associated rear top cylinders 20. The four-way valves 40 88a—95a each has a pair of lines 102 and 103 connected thereto. Each line 102—103 is connected to the associated front top cylinders 20. Thus by manipulating the valves, the sets of supporting members 16 and 17 may be projected 45 and retracted laterally to move the cleaner boxes at each side of the car, outwardly or inwardly.

45 The valves 90a—91a, 92a—93a are connected by pairs of lines 104—105 and 106—107 respectively, with the associated ends of the pushing 50 or brace cylinders 44. By proper manipulation of these valves, the cylinders 44 and rods 47 may be held in the desired relation providing that length of brace which holds the cleaner box, rigidly in working position against forces tending 55 to shift the same laterally.

The valves 13—82a are each connected by pairs of lines 108—109 respectively with the ends of the cylinders 43. By manipulating these 60 valves the effective length of the chains 38 may be determined and whereby the cleaner boxes may be caused to move forwardly or rearwardly relative to the car. Also by means of these valves the piston rods 42 may be caused to be extended to accommodate the movement of the 65 boxes into the non-working position on the car.

70 The valves of the groups of valves 74a—75a—76a—77a and 78a—79a—80a—81a are each connected by pairs of pipes 110—111—112—113, 75 114—115—116—117, respectively, each with opposite ends of an associated raising and lowering cylinder 28. Thus by proper manipulation of the valves above mentioned, the cleaner boxes may be raised or lowered to the desired elevation. When in the raised position, they may

be projected inwardly or outwardly by manipulation of the valves 88a—89a—94a—95a. When in the lowered position, proper manipulation of the valves, causes the associated cylinders 28 and piston rods 27 to hold the cleaner boxes to the desired working position in the ballast. The arrangement of the four-way valves, in connection with their associated parts are best shown in Fig. 10.

5 By turning the plug of any one of the various 10 four-way valves, to a neutral position as shown in dotted lines in Fig. 10, communication between the pipes or lines connected thereto is closed off so that the associated pistons and rods are locked against movement. This is an 15 important feature in that it enables an absolute control over said pistons and rods so that they are firmly held in the desired position against any forces tending to displace the same.

Another feature of importance in the hydraulic system is the reservoir 61 which is kept 20 but partially filled with hydraulic fluid to leave a space 61a at the top. Thus as such fluid enters the same from the hydraulic cylinders, through the pipes 85—59, it is freed of air and 25 gases and flows downwardly and is collected in the bottom of the reservoir. In this manner, the system is kept free of a foamless non-compressible fluid as no air can accumulate therein.

30 From the above, it is apparent that one or both cleaner boxes may be brought into the desired working position, either when progressing along a straight track or upon a curve. The cleaner boxes may be moved into the ballast to work at the desired depth and should an insurmountable obstruction be engaged thereby, the pin 40 breaks so that no damage results.

35 The apparatus described cleans rock ballast not only in the intertrack space but it also handles the outer shoulder equally as well and 40 at the same time when so desired. Should it be necessary to remove the excavator and cleaner box from its working position, to permit the passage of a train on the adjacent track, as often happens, it can be very quickly 45 and easily done. The operator in the cab has all the controls conveniently available. So, also in restoring the apparatus to working position, little time is required. This is an important item, as it reduces train interference to 50 a minimum. Again, the hydraulic means provided is positive in action and the parts stay in any placed position because the hydraulic fluid is not compressible.

55 While in describing the invention, I have referred in detail to the form, arrangement and construction of the various parts thereof, the same is to be considered only in the illustrative sense so that I do not wish to be limited thereto except as may be specifically set forth in the 60 appended claims.

I claim as my invention:

1. In an apparatus of the class described, a car, ballast excavating and cleaning mechanism carried by the car, and means for moving said 65 mechanism from its non-working position, outwardly and downwardly to its working position, said means also being operable to tilt said mechanism in any direction when in said working position to meet different working conditions. 70

2. In an apparatus of the class described, a car, ballast excavating and cleaning mechanism carried by the car, means for moving said mechanism from its non-working position, outwardly and downwardly to its working position, and 75

- means providing a universal connection between said mechanism and said means for moving the same.
3. In an apparatus of the class described, a car, ballast excavating and cleaning mechanism carried by the car, means for moving said mechanism from its non-working position outwardly and downwardly to its working position, and means providing a universal connection between said mechanism and said means for moving the same, the first mentioned means being operable to adjust said mechanism when in said working position to meet different working conditions.
4. In an apparatus of the class described, a car, ballast excavating and cleaning mechanism carried by the car, means for moving said mechanism from its non-working position on the car to a position laterally outward from the car, and means for moving said mechanism downwardly from said laterally outward position into its working position, certain of said means being operable to tilt said mechanism in any direction when in said working position to meet different working conditions.
5. In an apparatus of the kind described, a car, ballast excavating and cleaning mechanism carried by the car, means for moving said mechanism from its non-working position, outwardly and downwardly to its working position, said means also being operable to tilt said mechanism in any direction when in its working position to meet different working conditions, and means for holding said mechanism in the working position into which it has been moved, against lateral displacement by forces encountered when working in said working position.
6. In an apparatus of the kind described, a car, ballast excavating and cleaning mechanism carried by the car, means for moving said mechanism from its non-working position, outwardly and downwardly to its working position, said means also being operable to adjust said mechanism when in its working position to meet different working conditions, and means providing a draw bar connection between said mechanism and car.
7. In an apparatus of the kind described, a car, ballast excavating and cleaning mechanism carried by the car, means for moving said mechanism from its non-working position, outwardly and downwardly to its working position, means providing a draw bar connection between said mechanism and car and means for holding said mechanism in the working position into which it has been adjusted, against displacement by lateral forces encountered when working in said working position.
8. In an apparatus of the class described, a car, ballast excavating and cleaning mechanism carried by the car, means for moving said mechanism from its non-working position, outwardly and downwardly to its working position, and means providing a universal connection between said mechanism and said moving means whereby said mechanisms may be tilted in any direction.
9. In an apparatus of the class described, a car, ballast excavating and cleaning mechanism carried by the car, means for moving said mechanism from its non-working position, outwardly and downwardly to its working position, and means providing a universal connection at a plurality of points between said mechanism and said moving means whereby said mechanism may be tilted in any direction.
10. In an apparatus of the class described, a car, ballast excavating and cleaning mechanism carried by the car, means for moving said mechanism from its non-working position, outwardly and downwardly to its working position, and means providing a universal connection between each end of said mechanism and said moving means whereby said mechanism may be tilted in any direction.
11. In an apparatus of the class described, a car, ballast excavating and cleaning mechanism carried by the car, means for moving said mechanism from its non-working position, outwardly and downwardly to its working position, and means providing a universal connection between each of four corners of said mechanism whereby said mechanism may be tilted in any direction.
12. In an apparatus of the class described, a car, ballast excavating and cleaning mechanism carried by the car, means for moving said mechanism from its non-working position, outwardly and downwardly to its working position, means providing a universal connection between said mechanism and said means whereby said mechanism may be tilted in any direction, and means for holding said mechanism in said working position against lateral displacement by forces encountered when said mechanism is working in said working position.
13. In an apparatus of the kind described, a car, ballast excavating and cleaning mechanism, means including universal joints for suspending said mechanism from above and for raising and lowering the same, and means providing for a guided lateral movement of said suspending means from the car whereby said mechanism may be moved from its non-working position outwardly and downwardly to its working position.
14. In an apparatus of the kind described, a car, ballast excavating and cleaning mechanism, a plurality of supporting members for said mechanism extending transversely of the car in longitudinal spaced relation, means providing a guided movement for said members, means for projecting and retracting said members with respect to the side of the car, and means including universal joints carried by said members and operatively connected to said mechanism for raising and lowering the same out of and into working position.
15. In an apparatus of the kind described, a car, ballast excavating and cleaning mechanism, a plurality of supporting members for said mechanism extending transversely of the car in longitudinally spaced relation, means providing a guided movement for said members, means for projecting and retracting said members with respect to the side of the car, telescopic means between each of said members and said mechanism for raising and lowering said mechanism out of and into working position, and means providing a universal connection of said telescopic means with said members.
16. In an apparatus of the kind described, a car, ballast excavating and cleaning mechanism, a plurality of supporting members for said mechanism extending transversely of the car in longitudinally spaced relation, means providing a guided movement for said members, means for projecting and retracting said members with respect to the side of the car, telescopic means between each of said members and said mechanism for raising and lowering said mechanism

- out of and into working position, and means providing a universal connection of said telescopic means with said members and said mechanism respectively.
- 5 17. In an apparatus of the kind described, a car, ballast excavating and cleaning mechanism, a plurality of supporting members for said mechanism arranged above the same and extending transversely of the car in longitudinally spaced relation, means providing a guided movement for said members, means for projecting and retracting said members with respect to the side of the car, and hydraulic means supported from said members and operatively connected to said mechanism for raising and lowering the latter out of and into working position, said hydraulic means having a universal connection with said mechanism.
- 10 18. In an apparatus of the kind described, a car, ballast excavating and cleaning mechanism, a plurality of supporting members for said mechanism arranged above the same and extending transversely of the car in longitudinally spaced relation, means providing a guided movement for said members, means for projecting and retracting said members with respect to the side of the car, and hydraulic means supported from said members and operatively connected to said mechanism by means of joints permitting a universal tilting of said mechanism, for raising and lowering the latter out of and into working position.
- 15 19. In an apparatus of the kind described, a car, ballast excavating and cleaning mechanism carried by the car, hydraulic means for moving said mechanism in and out with respect to the car, hydraulic means for laterally bracing said mechanism when in said working position, 15 means providing a source of hydraulic fluid under pressure, means for connecting each of said hydraulic means with said source of hydraulic fluid, and means on the car for controlling the passage and return of said fluid to and from 20 each of said hydraulic means.
- 20

HARRY W. PROTZELLER.
